UNITED STATES PATENT OFFICE.

CHARLES A. HERMANN, OF MILWAUKEE, WISCONSIN.

MATTRESS OR THE LIKE.

1,398,297.

Specification of Letters Patent. Patented Nov. 29, 1921.

Application filed November 22, 1920. Serial No. 425,685.

To all whom it may concern:

Be it known that I, CHARLES A. HERMANN, a citizen of the United States, residing at Milwaukee, county of Milwaukee, and 5 State of Wisconsin, have invented new and useful Improvements in Mattresses or the like, of which the following is a specification.

This invention relates to mattresses, up- 10 holstery, cushions and other devices of a similar nature and is particularly directed to a resilient cushion in which springs are interposed between layers of such cushion.

Objects of this invention are to provide a 15 resilient cushion or mattress in which the interposed resilient members are so secured to the upper and lower covers as to minimize wear at the points of attachment and thereby produce a lasting structure; to so associate the springs and covers that accidental 20 displacement of the springs is rendered impossible; and to so form the spring itself that it coöperates with the covers to definitely position the spring.

25 Other objects are to provide a resilient cushion or mattress whose parts may be readily assembled and require a minimum number of operations; to provide a structure which may be economically produced; 30 and to generally simplify the construction of resilient cushions.

Other objects are to provide a resilient cushion in which the springs are held out of contact with each other or with other metallic parts to thereby both minimize wear and prevent noise; to so form the spring itself that each spring may be identical with all the other springs, and to provide a resilient cushion in which no additional treatment of 40 the burlap or other covering is required in order to adapt such cover for association with the springs.

An embodiment of the invention is shown in the accompanying drawing, in which:

45 Figure 1 is a fragmentary sectional elevation of a mattress or resilient cushion embodying the invention.

Fig. 2 is a plan view of the structure shown in Fig. 1 with a portion of the upper 50 cover removed to more clearly illustrate the spring construction.

In the practice of this invention, it is contemplated employing some form of strong fabric, such as burlap, for the casing of the

mattress or resilient cushion and to combine with this burlap, spacing resilient means so formed that no treatment of the burlap is necessary in order to affect the secure anchoring of the resilient means in position at its upper and lower ends. 55

The upper cover 1 and the lower cover 2 may conveniently be of burlap or other strong fabric and preferably of such fabric as is provided with a coarse weave. The spacing springs or resilient means comprise 60 helical springs 3 having upper and lower convolutions 4. These upper and lower convolutions are each provided with a series of 65 radially projecting enlargements 5, three of such enlargements being provided for each 70 terminal convolution and equally spaced about the periphery thereof. These enlargements comprise an elongated loop having a substantially rectangular shape and formed integral with the spring. The portions 8, which join the rectangular enlargements to the main portion of the convolution, are juxtaposed and are abruptly curved to 75 form constricted portions 6 which are bordered on one side by the inner edge of the rectangle and on the other side by the convolution itself. In this manner, the restricted portions 6 may be relatively long and narrow to 80 provide adequate room for any slight motion of the fabric engaged by these projections and 85 prevents disengagement of the fabric therefrom. The ends of each terminal convolution are provided with rounded eyelets 7 which prevent such ends from cutting into the fabric or otherwise protruding therefrom. 90

In assembling the elements of the mattress or resilient cushion, the warp and weft of the upper and lower coverings are slightly spread and one end of an enlargement 5 is 95 inserted within the opening thus formed and after such end has been projected through the opening to a convenient extent, the warp and weft are then slipped past the other end, thereby allowing the fabric to 100 assume substantially its original formation and to close about the connecting portions 8. Thereafter the other enlargements are correspondingly secured.

It is to be noted that all of the springs 105 may be identical and that a very simple manipulation of the fabric is required to definitely position the springs in place and

that, due to the identical construction of springs, a mattress or cushion of any desired extent may be formed by positioning the proper number of springs between the upper 5 and lower coverings.

It is to be understood that while this invention is particularly designed for mattresses, it is equally applicable to cushions, upholstery, and other similar articles, and 10 that while the springs have been described and illustrated as of identical construction, it is within the scope of this invention to provide different forms of springs, and, if desired, different types of springs within the 15 same structure.

It will thus be seen that a mattress or resilient cushion has been provided in which a minimum number of operations are necessary in assembling such device and in which 20 wear is minimized as the fabric is neither clamped or gripped between metal members nor is it restricted and prevented from any movement relative to the terminal convolutions. It is to be noted that a slight shifting 25 of the fabric is permitted as the mattress or resilient cushion assumes different positions in use, and that such shifting does not result in binding of the fabric as the fabric is at all times in contact only with smooth 30 faces and rounded corners.

I claim:

1. A cushioning device comprising covers, springs interposed between said covers and comprising a main body portion provided 35 with integral terminal convolutions bearing upon the inner sides of said covers, and means formed integral with said terminal convolutions to engage and positively retain said covers in contact with said terminal 40 convolutions.

2. A resilient cushioning device comprising covers, helical springs interposed between said covers and spacing them apart, said springs having terminal convolutions 45 formed integral with the main body portion thereof, and locking loops formed integral with said terminal convolutions and projecting from the said terminal convolutions and through said covers to definitely lock to said

covers and position said springs with reference to said covers. 50

3. A resilient cushioning device comprising covers, springs interposed between said covers and spacing them apart, said springs having integral terminal convolutions, and loops formed integrally with said terminal convolutions and projecting outwardly therefrom, said loops engaging said covers and projecting therethrough and having enlarged upper portions and constricted necks 60 connecting them with the terminal convolutions, whereby said terminal convolutions bear upon the inner sides of said covers and said loops retain said terminal convolutions with respect to said covers. 65

4. A resilient cushioning device comprising covers, springs interposed between said covers to resiliently space them apart, said springs each comprising a main body portion provided with integral terminal convolutions, and substantially rectangular loops formed integrally with said terminal convolutions and projecting from said convolutions and extending through said covers, said loops passing through said covers and 75 positioning said springs while permitting limited relative movement of said covers with respect to said end convolutions, whereby binding and wearing of said covers at the point of attachment to the springs is minimized. 80

5. A resilient cushioning device comprising fabric members, springs interposed between said fabric members, and having terminal convolutions in engagement with the 85 inner faces of said fabric members to resiliently space such members apart, substantially rectangular loops integrally joined to said terminal convolutions by curved connecting arms and extending through said fabric members and positioning a portion of said fabric members between said rectangular loops and said terminal convolutions, whereby said springs may be secured in position 90 between said fabric members without cutting said fabric members and whereby wear of said fabric members is minimized. 95

CHARLES A. HERMANN.
